(57) **CLAIM**

The ornamental design for a protective cap for metal posts
as shown and described.

DESCRIPTION

FIG. 1 is a top isometric view of a protective cap for metal posts showing our new design;

FIG. 2 is a bottom isometric view thereof;

FIG. 3 is another bottom isometric view thereof;

FIG. 4 is a top view thereof;

FIG. 5 is a bottom view thereof;

FIG. 6 is a front view thereof;

FIG. 7 is a rear view thereof;

FIG. 8 is a right-side view thereof; and,

FIG. 9 is a left-side view thereof.

The broken lines shown in FIGS. 3 and 5 illustrate portions
of the protective cap for metal posts that form no part of the
claimed design.
